UNITED STATES PATENT OFFICE.

LOUIS H. ERSHLER AND MAX HENDLER, OF HUDSON, NEW YORK.

BED-SPRING.

1,887,508.

Specification of Letters Patent.

Patented Apr. 20, 1920.

Application filed December 18, 1919. Serial No. 345,906.

To all whom it may concern:

Be it known that we, LOUIS H. ERSHLER and MAX HENDLER, citizens of the United States, residing at Hudson, in the county of 5 Columbia and State of New York, have invented certain new and useful Improvements in Bed-Springs, of which the following is a specification.

This invention relates to improvements in 10 bed springs.

An important object of the invention is to provide a bed spring which is readily demountable and assembled.

In the manufacture of bed springs they 15 are in the main so constructed that they may not be readily demounted for the purpose of compact arrangement for shipment. We have provided an extensible frame having the usual woven wire spring the parts of 20 which when in the assembled position are held in such assembled position by the action of the springs.

Other objects and advantages will be apparent throughout the course of the following description.

In the accompanying drawings wherein for the purpose of illustration is shown a preferred embodiment of our invention and wherein like numerals designate like parts 30 throughout.

Figure 1 is a fragmentary plan view of a bed spring embodying our invention,

Fig. 2 is a longitudinal section taken on the line 2—2 of Fig. 1,

Fig. 3 is a fragmentary end elevation of the spring,

Fig. 4 is a section taken on the line 4—4 of Fig. 2, and

Fig. 5 is a side elevation showing the 40 spring demounted and arranged for shipment, the woven wire spring being omitted for the purpose of clarity.

Referring now more particularly to the drawings the numerals 10 and 11 indicate 45 angle iron end frames. Secured to the angle iron end frame 10 at each end thereof by means of rivets 12 is a bracket 13. This bracket is provided with horizontal tubular member 14 of considerable length. The 50 horizontal tubular member has one end open as at 15 and a reduced opening formed in the opposite end as at 16. Secured to each end of the end member 11 by means of rivets 17 is a bracket 18 provided with a short 55 horizontally extending tubular member 19 having its inner end open as at 20.

Side bars 21 are provided, tubular in construction and having one end internally threaded as at 22 to receive an externally threaded adjusting member 23. This adjusting member is provided adjacent its outer end with an enlargement or shoulder 24 having a sliding fit with the interior tubular member 14. The outer end of the member 23 beyond the shoulder is reduced 60 to have a sliding fit with the opening 16 as at 25. This end 25 is provided with an opening 26 adapted to receive a suitable device for rotating the member 23. It will be obvious that it is not necessary to provide the 65 end 25 with the opening 26 as this end may be square to receive an operating wrench if desired.

The usual woven wire spring 27 is provided having at each end coiled springs 28 75 which engage the woven wire structure 27 with one end and the end members 10 and 11 with the other, the members 10 and 11 being provided with spaced openings 29 for this purpose.

In assembling the apparatus the side bars 21 are slipped into the tubular members 19 of the end member 11 and the adjusting member 23 is screwed into the side members as far as possible. The end member 10 is 85 then placed in position, the tubular sockets 14 receiving the ends of the side members 21 in which the operating members 23 are mounted. The ends 25 of the operating members project through the openings 16. 90 The spring is then placed in position and the operating members rotated until the sufficient tension is placed upon the spring 27. It will be obvious that this tension will hold the end members 10 and 11 upon the side 95 members 21.

When it is desired to ship or store the springs the operating members 23 are rotated to release the tension upon the spring 27 and the spring is unhooked from one of 100 the end members 10 or 11. The side members 22 are then removed and placed transversely of the tubular members 14 and raising thereon as shown in Fig. 5. The end member 11 is then inverted as shown in this 105 figure and placed in position and the spring 27 wound about the end members and hooked upon itself. It will be obvious that the above described arrangement gives a very compact article for shipment or storage. 110

As many changes are possible in the shape, size and arrangement of the various

parts herein shown and described we do not limit ourselves to the particular arrangement herein set forth, but may make any such changes without departing from the spirit of the invention, or the scope of the subjoined claim.

What we claim is:

In a bed spring, a pair of tubular side members provided in one end with internal screw threads, end members provided at each side thereof with tubular members slidably receiving the ends of said side members, a spring holding said end members in assembled position upon said side mem-

bers, and means engaging in the internal threads of said side members and abutting one of said end members for adjusting the tension of said spring, the tubular members being of greater length than those of the other end member.

In testimony whereof we affix our signatures in presence of two witnesses.

LOUIS H. ERSHLER.
MAX HENDLER.
